COMPOSITIONS AND METHODS FOR RAISING BLOOD PRESSURE WITH PROPYL AMINES

Werner Heinrich and Walter Heigel, Ludwigshafen am Rhine, Germany, assignors to Gebr. Giulini G.m.b.H., Ludwigshafen am Rhine, Germany, a corporation of Germany

No Drawing. Original application Nov. 19, 1963, Ser. No. 324,824, now Patent No. 3,345,411, dated Oct. 3, 1967. Divided and this application Oct. 7, 1964, Ser. No. 402,354

Int. Cl. A61k 27/00; C07c 85/00, 87/00

U.S. Cl. 424—330

21 Claims

ABSTRACT OF THE DISCLOSURE

Compositions and method of increasing blood pressure wherein the active material is of the formula:

wherein

R1 is alkyl having 2 to about 8 carbon atoms, and R2 is hydrogen, lower alkyl, or lower cycloalkyl.

This invention relates to propylamine derivatives and provides novel compounds of this class, new methods for production of such compounds, and methods for use of such compounds.

Said novel compounds and new methods for the production of such compounds are the subject of copending application Ser. No. 324,824, filed Nov. 19, 1963, now U.S. Patent 3,345,411. The instant application is a division of Ser. No. 324,824. Ser. No. 324,824 is a continuation-in-part of Ser. No. 231,018, filed Oct. 16, 1962, which in turn was a continuation-in-part of Ser. No. 54,542, filed Sept. 7, 1960, now abandoned. Priority under 35 U.S.C. 119 as is noted in the oath of the instant application is claimed.

The novel compounds of the invention are according to the following formula:

(I)

wherein:

- (a) R1 is alkyl having 2 to about 8 carbon atoms;
- (b) R2 is selected from the group consisting of hydrogen, lower alkyl, lower cycloalkyl.

The compounds may also be according to Formula V, infra.

Also provided by the invention, are medically acceptable salts of the above-described compounds.

The compounds of this invention possess valuable therapeutic properties which render them useful as vasoconstrictors and in particular for increasing blood pressure, stimulating the heart muscle, accelerating the heart rate and increasing cardiac output. Of outstanding importance is that they diminish or eliminate the undesirable depressive side effects of morphine on respiration. A distinctive characteristic of the compounds of the invention as vasoconstrictors is that they cause substantial blood pressure increase when administered to subjects having low blood pressure but do not cause such substantial blood pressure increase when administered to subjects having normal or high blood pressure.

2

R1 is preferably ethyl, propyl or butyl. With respect to the salts of these preferred compounds, the disclosure hereinafter with reference to salts of the vasoconstrictors of the invention apply, and with respect to the amines, these preferences apply to each of the secondary and primary derivatives.

The invention further provides the method of providing a vasoconstrictor effect. This is accomplished by administering a therapeutic amount of a compound according to Formula I.

Of the compounds according to Formula I, preferred compound groups are the following: R1 is ethyl, propyl, n-butyl, n-pentyl, or n-octyl, and R2 is hydrogen. This preference applies to the primary and to the secondary amines.

Another group of compounds within Formula I and constituting a preferred group of the invention, is the group wherein R1 is ethyl. Such compounds wherein R2 is cycloalkyl are particularly preferred. The salts of these compounds, desirably, are hydrochlorides. Specific compounds within this group are: 2 - ethyl-3,3-diphenylpropen-(2)-yl-amine, and cyclohexyl-[2-ethyl - 3,3 - di-phenyl-propen-(2)-yl]-amine. A compound to be accorded special mention in this group is cyclohexyl-[2-ethyl - 3,3 - di-phenyl-propen-(2)-yl]-amine in the form of its medicinally acceptable salt with hydrochloric, hydrobromic or hydroiodic acid. The compounds of this group, from the compounds of Formula I, are of the formula:

wherein R2 is hydrogen, lower alkyl, or lower cycloalkyl. This group includes the medicinally acceptable salts of the compounds of Formula III.

In Formula III where R1 is a lower alkyl group, or a cycloalkyl group, it is of the type conventionally present as a substituent in organic amino compounds designed for therapeutic application, in particular, lower alkyl or cycloalkyl, and preferably contains not more than about 6 carbon atoms. R2 can be for example, methyl, butyl, ethyl, propyl, isopropyl, isobutyl, secondary butyl, isoamyl hexyl, isohexyl, cyclohexyl and similar or related radicals.

The compounds of Formula III can be used in the form of the hydrochloride, but preferably are used as salts, e.g. acid addition salts. The salts are crystalline solids which are soluble in water and therefore constitute an advantageous embodiment of this invention.

The organic bases of the type shown in Formula III form salts with a variety of inorganic and organic acids conventionally used for therapeutic application of organic amino or imino bases and including hydrochloric, hydrobromic, hydroiodic, sulfuric, phosphoric, citric, lactic, maleic, acetic, benzoic, oxalic and related or similar acids. In many instances, the resulting salt crystallizes out of suitably concentrated solution on chilling or standing or may be precipitated by addition of a solvent, such as ether or benzene in which the salt is insoluble.

Another preferred group of compounds within the compounds of Formula I is the group represented by the formula:

wherein R1 is an alkyl group containing 2 to about 8 carbon atoms, especially 4 to about 8 carbon atoms. These compounds can be in the form of their medicinally acceptable acid addition salts. Particularly preferred compounds within this group are those in which R1 is n-butyl, n-pentyl, or n-octyl. What is said herein with reference

to salts of Formula I, applies also to salts of Formula IV.

Included within this group of Formula IV is 2-propyl-3,3-diphenyl-propen-(2)-yl-amine. This compound has been found well suited to the purposes of the invention.

Another preferred group of compounds of the invention is the group represented by the following formula:

in which R is alkyl, alkoxy, or halogen. These compounds can be in the form of their medicinally acceptable salts. Particular compounds of this group which have been found well suited for the purposes of the invention are the compounds wherein R is chloro, methyl or methoxy. Where R is alkyl, it is preferably a lower alkyl; where R is alkoxy, it is preferably a lower alkoxy. What has been said herein with reference to salts of compounds of Formula I, applies also to salts of compounds of Formula IV.

Compounds according to Formula I can be produced by hydrogenating compounds of the formula:

wherein R₁ is as described with reference to Formula I, to produce the corresponding alcohol-primary amine. If a secondary amine according to Formula I is to be produced, the said alcohol-primary amine can be reacted with an alkyl or cycloalkyl carbonyl compound under reducing conditions for the desired alkylation. The product propene amine can then be obtained by dehydrating the alcohol-primary or -secondary amine, as the case may be.

The hydrogenation of the nitrile can be a catalytic hydrogenation. A desirable catalyst for the reaction is platinum, and the reaction is preferably carried out in a solvent for the nitrile, for example acetic acid or methanol.

The dehydration of the alcohol-amine can be carried out by the known and conventional dehydrating methods, and preferably employing as dehydrating agent gaseous hydrogen chloride with the alcohol-amine in solution. Solvents such as acetic acid can be used, and the dehydration can be effected by heating the solution under reflux for a time sufficient to complete the dehydration.

Where, in accordance with Formula V, halogen is present, the hydrogenation is with lithium aluminum hydride rather than catalytically. In such cases the nitrile containing chloro substituent can first be dehydrated to form an acrylonitrile derivative and this derivative can be hydrogenated with lithium aluminum hydride to form the propane-primary amine.

A further feature of the invention is provision of a process for the production of primary amines. Thus, the invention provides for production of primary amines such as amines of Formula I wherein R₂ is hydrogen. The procedure involves catalytically hydrogenating the corresponding 2-hydroxypropionitrile to form therefrom the corresponding alcohol-primary amine, and dehydrating the alcohol-primary amine to form the product primary amine.

Where the primary amine to be produced includes halogen, as in Formula V, the corresponding 2-hydroxypropionitrile can be dehydrated to produce the corresponding acrylonitrile, and the acrylonitrile can be hydrogenated to form the primary amine.

Another feature of the invention is the provision of a process for production of secondary amines. Thus, there

can be produced compounds according to Formula I wherein R₂ is lower alkyl or lower cycloalkyl. In this procedure, the corresponding alcohol-primary amine, wherein in the hydroxy group of the alcohol is in the 3-position, is contacted with an alkyl or cycloalkyl carbonyl compound under reducing conditions to produce the corresponding alcohol-secondary amine, and the alcohol-secondary amine is dehydrated to produce the secondary amine product.

Further details of preparation of compounds of the invention are set out below.

COMPOUNDS OF FORMULA III

Compounds of this invention can be prepared utilizing the step of catalytically hydrogenating 1-ethyl-2-hydroxy-2,2-diphenyl-propionitrile to form the corresponding 2-ethyl-3-hydroxy-3,3-diphenyl-propyl-amine.

A particularly advantageous catalyst for use in hydrogenating the nitrile is platinum. The hydrogenation reaction is preferably carried out in a solvent for the nitrile, for example acetic acid or methanol.

The 1-ethyl-2-hydroxy-2,2-diphenyl-propionitrile, which is necessary as basic product, is obtained by condensation of benzophenone and butyronitrile, which was proposed by Lettre.

The 2 - ethyl - 3,3 - diphenylpropen - (2) - yl - amine is prepared by dehydration of the 2-ethyl-3-hydroxy-3,3-diphenylpropylamine. The dehydration is carried out by the known and conventional dehydrating methods, and preferably there may be employed as dehydrating agent gaseous hydrogen chloride with the 2-ethyl-3-hydroxy-3,3-diphenylpropylamine in solution. As solvent for the 2-ethyl-3-hydroxy-3,3-diphenylpropylamine, acetic acid can be used. The dehydration is preferably carried out by heating the solution under reflux for a time sufficient to complete the dehydration.

The mono-alkylated derivatives of the hydroxylated compound are prepared by reacting the compound containing a primary amino group with an alkyl or cycloalkyl carbonyl compound under reducing conditions, and preferably the alkylation is achieved by catalytic hydrogenation of the free base in the presence of carbonyl compounds. Thus, in accordance with the invention, alkylating of the 2-ethyl-3-hydroxy-3,3-diphenyl-propylamine is carried out and thereafter the mono-alkylated 2-ethyl-3-hydroxy-3,3-diphenyl-propylamine is subjected to dehydration to thereby obtain the mono-alkylated 2-ethyl-3,3-diphenyl-propene-amine.

Alternatively, the mono-alkylated derivatives may be obtained by reacting the 2-ethyl-3-hydroxy-3,3-diphenylpropyl-amine with carbonyl compounds to form the corresponding 1,3-oxazine and, through catalytic hydrogenation, to split the 1,3-oxazine to form the amino alcohol.

Example 1.—Preparation of 1-ethyl-2-hydroxy-2,2-diphenylpropionitrile

54.6 g. of benzophenone and 20.7 g. of butyronitrile are dissolved in 400 ml. of absolute ether. 16 g. of sodium amine powder are added and the mixture is boiled for 7 hours at a temperature of 40° C. under reflux. Thereafter, the solution is given into 500 ml. of ice/water and stirred for 5 min. The reaction product separates at once in a crystalline form (the raw yield amounts to 66 g.=88%) which is recrystallized by means of benzene with a loss of 20%. The melting point thereby obtained is 162° C.

Example 2.—Preparation of 2-ethyl-3-hydroxy-3,3-diphenylpropylamine

10 g. of 1-ethyl-2-hydroxy-2,2-diphenyl-propionitrile are dissolved in 200 ml. of methanol. 10 ml. of acetic acid are added to the mixture, and the mixture is hydrogenated in the presence of platinum as catalyst. After the hydrogen uptake or consumption has ceased, the reaction is interrupted, the catalyst is filtered off and the filtrate is evaporated in *vacuo* to dryness. The residue is dissolved in water, and, after the addition of one ml. of hydrochloric

acid, the solution is extracted with ether. The acidified ether-phase is discarded. The aqueous phase is made alkaline with ammonia, whereby the base crystallizes out. The crystals are recovered and crystallized from methanol. The melting point of the 2-ethyl-3-hydroxy-3,3-diphenylpropylamine thereby obtained is 132° C.

Example 3.—Preparation of 2-ethyl-3,3-diphenyl-propen-(2)-yl-amine-hydrochloride

5 g. of 2-ethyl-3-hydroxy-3,3-diphenylpropylamine are dissolved in 50 ml. of acetic acid. Gaseous hydrogen chloride is passed through the solution for 10 minutes, and thereafter the solution is boiled for one hour under reflux. The solution is then distilled to dryness. The residue is dissolved in water and the acidified solution extracted with ether. The aqueous phase is separated, made alkaline with ammonia and extracted with ether. The ether phase is dried over sodium sulfate, the ether distilled off and the residue is dissolved in methanolic hydrogen chloride. On the addition of absolute ether, the hydrochloride of 2-ethyl-3,3-diphenyl-aminopropen-(2)-yl is crystallized out. The crystalline substance thereby obtained has a melting point of 232° C.

Example 4.—Cyclohexyl-[2-ethyl-3-hydroxy-3,3-diphenyl-propyl]-amine

6 g. of 2-ethyl-3-hydroxy-3,3-diphenyl-propylamine are dissolved in 200 ml. of methanol. 10 ml. of freshly distilled cyclohexanone are added to the solution and the solution is hydrogenated in the presence of a platinum catalyst. The hydrogen consumption takes place very quickly. The catalyst is filtered off and the filtrate concentrated to dryness. The residue is taken up in dilute hydrochloric acid and extracted with ether. The hydrochloride salt which is partially recovered from the ether phase, is crystallized out from methanol ether. The crystals thereby obtained have a melting point of 180–182° C. The water phase is made alkaline with ammonia and thereafter extracted with ether. After drying over sodium sulfate, the ether extract is subjected to distillation. The residue thereby obtained recrystallized from a mixture of acetone and water in the ratio of 2:1. The base thus recovered has a melting point of 78–80° C.

Example 5.—Cyclohexyl-[2-ethyl-3,3-diphenyl-propen-(2)-yl]-amine-hydrochloride

3.37 g. of cyclohexyl-[2-ethyl-3-hydroxy-3,3-diphenyl-propyl]-amine are dissolved in 50 ml. of acetic acid and gaseous hydrogen chloride is passed through the solution until the reaction mixture is strongly acidic. The mixture is heated for two hours in a boiling water bath. The acetic acid solution is thereafter distilled under *vacuo* to dryness. The residue is dissolved twice in 50 ml. portions of methanol, and each time the solution is evaporated to dryness. The final residue is dissolved in a small amount of methanol and the hydrochloride salt crystallized out by addition of absolute ether. The crystalline substance thereby obtained has a melting point of 212–215° C.

Compounds having alkyl substituents on the amino group other than the instances disclosed in the examples may be obtained by carrying out the foregoing experiments using in the alkylation reaction other alkyl or cycloalkyl carbonyl compounds, as for example methyl, cyclohexyl, pentyl, hexyl, butyl, diethyl, etc. It is furthermore possible to prepare, in lieu of hydrochlorides, corresponding salts of other acids by contacting the base in the form of its solution with an acid, as for example hydrobromic, hydroiodic, phosphoric, citric, oxalic, in place of the hydrochloric acid, until the reaction mixture is strongly acidic. The said solution may have to be concentrated somewhat for crystallization, upon chilling, to occur.

COMPOUNDS OF FORMULA IV

These compounds can be made by reactions as are disclosed above for the compounds of Formula III.

Example 6a.—2-n-butyl-3-hydroxy-3,3-diphenyl-propyl-amine

14 g. 1-n-butyl-2-hydroxy-2,2-diphenyl-propionitrile are dissolved in 350 ml. glacial acetic acid, 0.5 g. of platinum catalyst are added and then hydrogenized. After completed hydrogenation, the catalyst is filtered off, and the filtrate is evaporated in vacuum to dryness. The residue is treated with water, treated with hydrochloric acid until the acid reaction, filtered off from the undissolved material, and extracted with ether. The aqueous phase is made alkaline with ammonia solution, extracted with ether and the ether part dried via sodium sulfate. After distilling off of the ether remains the 2-n-butyl-3-hydroxy-3,3-diphenyl-propyl-amine is obtained. Melting point: 84° C.

Example 6b.—2-n-butyl-3,3-diphenyl-propen-(2)-yl-amine-hydrochloride

17 g. 2-n-butyl-3-hydroxy-3,3-diphenyl-propyl-amine are dissolved in 100 ml. glacial acetic acid. This solution is saturated with hydrogen chloride gas and subsequently heated for three hours to 100° C. The acetic acid is distilled off in vacuum. The residue is dissolved in a little methanol and the 2-n-butyl-3,3-diphenyl-propen-(2)-yl-amine-hydrochloride is precipitated by addition of absolute ether. Melting point: 161° C.

Example 7a.—2-n-pentyl-3-hydroxy-3,3-diphenyl-propyl-amine

Through hydrogenation of 1-n-pentyl-2-hydroxy-2,2-diphenyl-propionitrile one obtains the 2-n-pentyl-3-hydroxy-3,3-diphenyl-propyl-amine in analogous manner according to Example 6a. Melting point: 57° C.

Example 7b.—2-n-pentyl-3,3-diphenyl-propen-(2)-yl-amine-hydrochloride

The solution of 9.5 g. 2-n-pentyl-3-hydroxy-3,3-diphenyl-propyl-amine in 100 ml. glacial acetic acid is saturated with hydrogen chloride and subsequently heated for three hours to 100° C. The acetic acid is distilled off in vacuum, and the 2-n-pentyl-3,3-diphenyl-propen-(2)-yl-amine-hydrochloride remaining is recrystallized from benzene. Melting point: 138–140° C.

Example 8a.—2-n-octyl-3-hydroxy-3,3-diphenyl-propyl-amine

50 Through hydrogenation of 1-n-octyl-2-hydroxy-2,2-diphenyl-propionitrile one obtains the 2-n-octyl-3-hydroxy-3,3-diphenyl-propyl-amine in analogous manner according to Example 6a. Melting point: 88° C.

Example 8b.—2-n-octyl-3,3-diphenyl-propen-(2)-yl-amine-hydrochloride

The solution of 38.5 g. 2-n-octyl-3-hydroxy-3,3-diphenyl-propyl-amine in 200 ml. glacial acetic acid is saturated with hydrogen chloride gas and subsequently heated for three hours to 100° C. The crystals of 2-n-octyl-3,3-diphenyl-propen-(2)-yl-amine-hydrochloride remaining behind after distilling off of the acetic acid in vacuum, are washed-out with absolute ether. Melting point: 157° C.

65 The comments made above with respect to the examples under Formula III as to substitutions in the examples, apply to the foregoing examples of compounds of Formula IV.

COMPOUNDS OF FORMULA V

70 These compounds can be produced in a manner analogous to production of compounds of Formula III, that is, through hydrogenation of 1-ethyl-2-hydroxy-2,2-diaryl-propionic nitrile and separation of water. In the cases in which a halogen substitution exists, hydrogenation can be 75 by means of lithium aluminum hydride. In all other cases,

the reduction can be effected catalytically. In these reactions, there is formed a mixture of two cis-trans-forms.

Example 9.—2-ethyl-3-phenyl-3-(p-methyl-phenyl)-propen-(2)-yl-amine-hydrochloride

13.3 g. 1-ethyl-2-hydroxy-2-phenyl-2-(p-methyl-phenyl)-propionic nitrile are dissolved in 400 ml. glacial acetic acid, 200 mg. platinum catalyst are added and subsequently hydrogen is introduced. After completion of hydrogen absorption, one filters off from catalyst, and the filtrate is evaporated in vacuum until dry. The residue is dissolved in water, treated with hydrochloric acid until the acid reaction, filtered off from the residue, and the filtrate added drop by drop into 20% soda lye. Therein the 2-ethyl-3-hydroxy-3-phenyl-3-(p-methyl-phenyl)-propyl-amine precipitates. Melting point: 88-90° C.

4.8 g. 2-ethyl-3-hydroxy-3-phenyl-3-(p-methyl-phenyl)-propyl-amine are dissolved in 50 ml. glacial acetic acid. This solution is saturated with hydrogen chloride gas and subsequently heated for 3 hours to 100° C. The acetic acid is distilled off in vacuum. The residual crystals are dissolved in methanol and the 2-ethyl-3-phenyl-3-(p-methyl-phenyl)-propen-(2)-yl-amine hydrochloride precipitated through addition of absolute ether. Melting point: 223-225° C.

Example 10.—2-ethyl-3-phenyl-3-(p-methoxyphenyl)-propen-(2)-yl-amine-sulfate

Through hydrogenation of 1-ethyl-2-hydroxy-2-phenyl-2-(p-methoxy-phenyl)-propionic nitrile one obtains the 2-ethyl-3-hydroxy-3-phenyl-3-(p-methoxyphenyl)-propyl-amine in the manner described in Example 9. Melting point: 148° C.

Into a solution of 4.2 g. 2-ethyl-3-hydroxy-3-phenyl-3-(p-methoxyphenyl)-propyl-amine one introduces for 25 minutes dry hydrogen chloride gas and subsequently heats for 2½ hours to 100° C.; thereafter, the material distilled until dry. The residue is dissolved in water, made alkaline with diluted soda lye, and then extracted with ether. The ether part is dried with sodium sulfate, the ether distilled off, and the thus obtained 2-ethyl-3-phenyl-3-(p-methoxyphenyl)-propen-(2)-yl-amine converted into its sulfate. The substance melts at 145-165° C.

Example 11.—2-ethyl-3-phenyl-3-(p-chlorophenyl)-propen-(2)-yl-amine-hydrochloride

To a hot solution of 16.3 g. 1-ethyl-2-hydroxy-2-phenyl-2-(p-chlorophenyl)-propionic-nitrile in 300 ml. absolute benzene, there is very quickly added 20 g. phosphorous-pentoxide. The reaction mixture is boiled for 45 minutes under reflux, the benzene solution decanted, and the residue is twice boiled-out with each 100 ml. absolute benzene. After distilling off of the benzene, there remains the 1-ethyl-2-phenyl-2-(p-chlorophenyl)-acrylo-nitrile in almost quantitative yield as yellowish oil.

A solution of 5.4 g. 1-ethyl-2-phenyl-2-(p-chlorophenyl)-acrylo-nitrile in 20 ml. absolute ether is added drop by drop within half an hour to a suspension of 0.76 g. lithium aluminum hydride in 100 ml. absolute ether under ice-cooling and stirring, so that the temperature does not rise above 5° C. The reaction mixture is still further stirred for half an hour and then treated, successively, with 0.8 ml. water, 0.6 ml. 20% soda lye, and 2.8 ml. water. The yellow-colored ether solution is then decanted from the granular precipitate, and this is then washed three times with 30 ml. absolute ether. The 2-ethyl-3-phenyl-3-(p-chlorophenyl)-propen-(2)-yl-amine present in the ether solution is isolated as hydrochloride. Melting point: 208-211° C.

As noted above, with reference to compounds of For-

mula III, in the case of the compounds of Formula V various acid addition salts of the compounds can be provided.

2 - PROPYL DERIVATIVE OF COMPOUNDS OF FORMULA III

Through hydrogenation of 1-propyl-2-hydroxy-2-diphenyl-propionic-nitrile and subsequent separation of water from the 2-propyl-3,3-diphenyl-3-hydroxy-propyl-amine formed, the 2-propyl-3,3-diphenyl-propen-(2)-yl-amine can be obtained. The starting material for production of the 2-propyl derivatives can be obtained in a manner analogous to the manner in which the starting material for the compounds of Formula III is obtained.

Example 12.—2-propyl-3,3-diphenyl-propen-(2)-yl-amine hydrochloride

13.1 g. 1-propyl-2-hydroxy-2,2-diphenyl-propionic-nitrile are dissolved in 400 ml. glacial acetic acid, 200 mg. platinum catalyst are added, and subsequently hydrogen is introduced. After hydrogen absorption ceases, the catalyst is filtered off, and the filtrate evaporated in vacuum until dry. The residue is dissolved in water, treated with hydrochloric acid until acid reaction, the residue is filtered off, and the filtrate added drop by drop into 20% soda lye. The precipitated 2-propyl-3,3-diphenyl-3-hydroxy-propyl-amine is recovered. Melting point: 108-110° C.

4.8 g. 2-propyl-3,3-diphenyl-3-hydroxy-propyl-amine are dissolved in 50 ml. glacial acetic acid. This solution is saturated with hydrogen chloride gas and subsequently heated for 3 hours at 100° C. The acetic acid is distilled off in vacuum. The crystals remaining behind are dissolved in methanol and the 2-propyl-3,3-diphenyl-propen-(2)-yl-amine hydrochloride is precipitated through addition of absolute ether. Melting point: 213-215° C.

What is said above with reference to salts of the compounds of Formula III, applies as well to the salts of the 2-propyl derivatives.

UTILITY DATA

The compounds of the invention are substantially more effective than the corresponding 2-methyl derivatives. This can be demonstrated by tests on anesthetized animals to which the 2-methyl derivative and a 2-ethyl derivative have been administered. Further information on utility follows.

COMPOUNDS OF FORMULA III

The following details were found by experimenting with 2-ethyl-3,3-diphenyl-propen-(2)-yl-amine hydrochloride on animals.

(1) Acute toxicity:

DL 50, white mouse, i.v. 35.5 mg./kg.

DL 50, white mouse, p.o. 87.5 mg./kg.

DL 50, white mouse, s.c. approx. 100 mg./kg.

DL 50, white rat, p.o. 183 mg./kg.

(2) Chronic toxicity:

White rat, per os 18.3 mg./kg. pro die, 20 animals: during a 30 days' feeding body weight and general behavior normal. No toxic signs. Action of erythrocytes and leucocytes within physiological limits. Macroscopic and microscopic no organic conditions.

(3) Picture of actions:

For the most part chronic convulsions with point of action on motor brain centers; besides tonic components of convulsion (stimulative effect) vasomotor center, breath center, mainly centrally conducted increase of blood pressure, central excitation.

- (4) The effect on the blood pressure in cats under chloralose-urethane-anaesthesia:
- 0.5 mg./kg. i.v.: increase of blood pressure of 40–60 mm. Hg, effective for 6–8 minutes;
- 0.1 mg./kg. i.v.: increase of blood pressure of 30–50 mm. Hg, effective for about 5 minutes; 5
- 1 mg./kg. i.v.: increase of blood pressure of 45–60 mm. Hg, with longer efficiency;
- 2 mg./kg. i.v.: increase of blood pressure of 50–60 mm. Hg, with long efficiency. 10

With normal or reduced initial blood pressure the hypertensive effect is stronger than with an increased initial blood pressure.

(5) Effect on the experimentally conducted circulatory collapse in cats: 15

(a) Circulatory collapse by Evipan-Sodium continuous infusion:

0.1–2.0 mg./kg. i.v.: strong hypertensive effect for a prolonged time

(b) Circulatory collapse by Acetylcholin continuous infusion:

0.1–2.0 mg./kg. i.v.: stronger hypertensive effect with long efficiency. 25

(6) Effect on the breathing in narcotized cats:

0.1–2.0 mg./kg. i.v.: strong stimulation of breathing.

(7) Effect on the heart:

(a) frog, in situ perfused according to Bülbring. 30

0.1 mg. percent (1:1,000,000): no change of frequency and minute volume

0.4 mg. percent (1:250,000): no influence on frequency and minute volume

1 mg. percent (1:100,000): decrease of minute volume 35 with constant frequency.

(b) ECG in guinea-pigs:

Doses of 0.63–2.0 mg./kg. cause no significant change in ECG apart from a temporary decrease of frequency. 40

(8) Stimulative effect in rabbits under urethane anaesthesia:

0.1–2.5 mg./kg. i.v.: strong stimulative effect.

(9) Effect on the breathing of rabbits under morphine: 45

The damaged breathing caused by an intravenous injection of 5–7 mg./kg. morphine hydrochloride (decrease of the volume and frequency of breathing) is normalized by an intravenous injection of 0.1–2.5 mg./kg. 50

COMPOUNDS OF FORMULA IV

It has been found for compounds of Formula I, there is a pronounced dependence of duration of blood pressure rising effect on the length of the alkyl group in the 2-position, i.e. R_1 in Formula I. As the length of the alkyl chain increases, the duration of effect increases. For 0.5 mg./kg. of 2-propyl-3,3-diphenyl-propen-(2)-yl-amine has a duration of 30–40 minutes on the blood pressure of the cat in urethane chloralose narcosis, while 55 0.5 mg./kg. of 2-butyl-3,3-diphenyl-propen-(2)-yl-amine has a duration of up to 4 hours.

COMPOUNDS OF FORMULA V

These compounds are especially preferred since they have an especially pronounced effect on blood pressure and this effect is particularly long-lasting.

Effects on the blood pressure of the cat under urethane chloralose narcosis for compounds of Formula V, as follows, were noted.

2 - ethyl - 3 - phenyl - 3 - (p - chlorophenyl) - propen-(2)-yl-amine as hydrochloride, gluconate and methanesulfonate:

1 mg./kg. i.v.: blood pressure increase of 40–50 mm. Hg, lasting about 30–40 minutes;

- 2 mg./kg. i.v.: blood pressure increase of 60 mm. Hg, lasting about 2–4 hours;
- 3 mg./kg. i.v.: blood pressure increase of 60–80 mm. Hg, lasting about 4 hours and longer.

For lower starting blood pressure the blood pressure increase effect is stronger and lasts longer than in normal or high starting blood pressure.

1 - (3 - hydroxyphenyl) - 1 - hydroxy - 2 - N - ethylaminoethane-hydrochloride of the structural formula

- 1 mg./kg. i.v.: blood pressure increase of about 20 mm. Hg, lasting about 4–8 minutes;
- 2 mg./kg. i.v.: blood pressure increase of 20–30 mm. Hg, lasting about 4–8 minutes;
- 3 mg./kg. i.v.: blood pressure increase of 40–60 mm. Hg, lasting about 4–8 minutes;
- 4 mg./kg. i.v.: blood pressure increase of 40–60 mm. Hg, lasting about 4–8 minutes.

ephedrine:

- 1 mg./kg. i.v.: blood pressure increase of 20–40 mm. Hg, lasting about 30–40 minutes;
- 2 mg./kg. i.v.: blood pressure increase of 40–50 mm. Hg, lasting about 30–40 minutes;
- 3 mg./kg. i.v.: blood pressure increase of 40–50 mm. Hg, lasting about 30–40 minutes.

In all cases, the starting blood pressure was about the same and was between 80 and 100 mm. Hg.

PROPYL DERIVATIVES OF COMPOUNDS OF FORMULA III

Compounds of Formula III having a propyl group in the 2-position instead of an ethyl group, are of particular interest because of their long-lasting blood pressure effect.

Effects as follows were noted for the blood pressure of the cat in urethane chloralose narcosis:

2-propyl-3,3-diphenyl-propen-(2)-yl-amine as hydrochloride, gluconate and methanesulfonate:

- 0.5 mg./kg. i.v.: blood pressure increase of 40–60 mm. Hg, lasting about 30–40 minutes;
- 1.0 mg./kg. i.v.: blood pressure increase of 45–60 mm. Hg, lasting about 2–3 hours;
- 2.0 mg./kg. i.v.: blood pressure increase of 70–90 mm. Hg, lasting about 3–4 hours, and longer.

For lower starting blood pressure the blood pressure increasing effect is stronger and lasts longer than in the case of raised or normal starting blood pressure.

1 - (3 - hydroxyphenyl) - 1 - hydroxy - 2 - N - ethylaminoethane hydrochloride of the structural formula:

- 1 mg./kg. i.v.: blood pressure increase of about 20 mm. Hg, lasting about 4–8 minutes;
- 2 mg./kg. i.v.: blood pressure increase of 20–30 mm. Hg, lasting about 4–8 minutes;
- 3 mg./kg. i.v.: blood pressure increase of 40–60 mm. Hg, lasting about 4–8 minutes;
- 4 mg./kg. i.v.: blood pressure increase of 40–60 mm. Hg, lasting about 4–8 minutes.

The effect of ephedrine is as reported above for compounds of Formula V. In all cases, the starting blood pressure was about the same and was between 80 and 100 mm. Hg.

COMPOSITIONS

The compounds in accordance with the invention may be given in dosage form hypodermically or intramuscularly in the form of HCl salt, or in the form of their salts in isotonic physiologically acceptable solutions, as for example water saline or peanut oil. Locally, they may be used in solution as a spray and in ointment.

The exact dosage in each instance is entirely dependent on the effect sought to be achieved, the mode of administration employed and the degree of caution which must be observed. Dosage can be, for example, 15 mg. for parenteral administration. In any instance, there is employed at least that amount of the compound, i.e. active agent, necessary to produce the desired physiological effect, but less than that amount producing an undesired toxic effect.

The compounds of the invention, as can be readily appreciated, also constitute valuable tools for use in medical research, as for instance in connection with animal experiments and in particular in the study of their effect on the blood pressure by stimulating the contraction of the muscular tissue of the capillaries and arterioles.

What is claimed is:

1. A method of raising blood pressure which comprises administering to the subject at least a therapeutic amount of a compound of the formula:

(I)

wherein:

- (a) R1 is alkyl having 2 to about 8 carbon atoms;
- (b) R2 is selected from the group consisting of hydrogen, lower alkyl and lower cycloalkyl;

or medicinally acceptable salts thereof.

2. The method of claim 1, wherein R1 is propyl.

3. The method of claim 1, wherein R1 is n-butyl.

4. The method of claim 1, wherein R1 is n-pentyl.

5. The method of claim 1 wherein R1 is n-octyl.

6. A method of raising blood pressure which comprises administering to the subject at least a therapeutic amount of a compound of the formula:

(III)

wherein R2 is selected from the group consisting of hydrogen, lower alkyl, and lower cycloalkyl, or medicinally acceptable salts thereof.

7. The method of claim 6 wherein R2 is cycloalkyl.

8. The method of claim 6, wherein said compound is in the form of the hydrochloride.

9. The method of claim 6, wherein R2 is hydrogen.

10. The method of claim 6, wherein R2 is cyclohexyl.

11. The method of claim 6, wherein R2 is cyclohexyl and said compound is in the form of a medicinally acceptable salt with a member selected from the group consisting of hydrochloric, hydrobromic, and hydroiodic acid.

12. A method of raising blood pressure which comprises administering to the subject at least a therapeutic amount of a compound of the formula:

(IV)

wherein R1 is an alkyl radical containing 2 to about 8 carbon atoms, or medicinally acceptable salts thereof.

13. Method of claim 12, wherein R1 is n-pentyl.

14. Method of claim 12, wherein R1 is n-butyl.

15. Method of claim 12, wherein R1 is n-octyl.

16. Method of claim 12, wherein said compound is in the form of the hydrochloride.

17. A method of raising blood pressure which comprises administering to the subject at least a therapeutic amount of 2-propyl-3,3-diphenyl-propen-(2)-yl-amine or medicinally acceptable salts thereof.

18. A method of raising blood pressure which comprises administering to the subject at least a therapeutic amount of a compound

(V)

in which R is selected from the group consisting of alkyl, alkoxy and halogen, or medicinally acceptable salts thereof.

19. Method of claim 18, wherein R is chloro, methyl, or methoxy.

20. A therapeutic agent for parenteral administration in the form of a physiologically acceptable solution, comprising a blood pressure raising amount of a compound of the following formula,

wherein:

- (a) R1 is alkyl having 2 to about 8 carbon atoms;
  - (b) R2 is selected from the group consisting of hydrogen, lower alkyl and lower cycloalkyl;
- or a medicinally acceptable salt thereof dissolved in a vehicle suitable for administration by injection.

21. A therapeutic agent for topical administration in the form of a spray or ointment, comprising a blood pressure raising amount of a compound of the following formula

wherein:

- (a) R1 is alkyl having 2 to about 8 carbon atoms;
  - (b) R2 is selected from the group consisting of hydrogen, lower alkyl and lower cycloalkyl;
- or a medicinally acceptable salt thereof, dissolved in a vehicle suitable for such administration.
